(57) **CLAIM**

The ornamental design for a tab forming tool, as shown and described.

DESCRIPTION

FIG. 1 is a first top perspective view of the tab forming tool;

FIG. 2 is a second top perspective view of the tab forming tool;

FIG. 3 is a first bottom perspective view of the tab forming tool;

FIG. 4 is a second bottom perspective view of the tab forming tool;

FIG. 5 is a top plan view of the tab forming tool;

FIG. 6 is a bottom plan view of the tab forming tool;

FIG. 7 is a first end elevation view of the tab forming tool;

FIG. 8 is a second end elevation view of the tab forming tool;

FIG. 9 is a first side elevation view of the tab forming tool;
and,

FIG. 10 is second side elevation view of the tab forming tool.

The broken lines depict portions of the tab forming tool in
which the design is embodied that are not considered part of
the claimed design.
